UNITED STATES PATENT OFFICE.

JESSE FRANKLIN PRATHER, OF MOUNT AIRY, NORTH CAROLINA.

HUMIDIFIER FOR TOBACCO.

1,249,490.

Specification of Letters Patent. Patented Dec. 11, 1917.

Application filed February 23, 1917. Serial No. 150,456.

To all whom it may concern:

Be it known that I, JESSE F. PRATHER, a citizen of the United States of America, and a resident of Mount Airy, county of Surry, 5 State of North Carolina, have invented certain new and useful Improvements in Humidifiers for Tobacco, of which the following is a full and clear specification.

The object of this invention is to provide 10 a moistening attachment for cigarette, cigar and tobacco boxes and jars, and the invention consists in certain novel features of construction hereinafter described and claimed.

15 In the drawing—

Figure 1 is a perspective view of a cigarette box provided with my device;

Fig. 2 is a detail perspective view of the 20 holder for the sponge or other absorbent;

Fig. 3 is a detail vertical sectional view through the cover of the box and the sponge holder therein; and

Fig. 4 is a horizontal sectional view on the line 4—4 of Fig. 3.

25 The holder for the sponge or other absorbent consists of a substantially rectangular box having an open top and a closed bottom, one or more solid walls *a* and one or more foraminous walls *b*. One of the solid walls 30 is provided with a dove-tail groove formed by bending the wall inwardly, this groove being open at both its upper and lower ends. On the interior of the back wall of the cover of the cigarette box or other tobacco receptacle is fastened a vertical flange *c* whose edges are beveled to fit snugly within the dove-tail groove in the sponge holder. After the sponge or other absorbent is put into the holder, the holder is slipped, open side 35 upward, onto the rib or flange *c*, the fit of the flange in the groove being sufficiently tight to frictionally hold the sponge receptacle in place against the top wall of the

cover, the top wall of the cover thus serving as a cover for the sponge-holding receptacle. 45 The depth of the sponge-holding receptacle is less than that of the cover, so that when the cover is closed the bottom of the sponge-holder will not contact with the cigars, cigarettes or tobacco in the box or jar. It will be 50 observed that the moisture from the sponge passes out through the foraminous walls *b* and thus keeps the tobacco goods properly moistened.

It will be observed that it is essential in 55 my device to employ a flanged or cupped lid, that is, a lid having a back wall adapted to support the absorbent-holder above the tobacco space of the box.

It will be observed that the rib or flange *c* 60 terminates short of the lower edge of the back wall of the lid, thereby leaving the entire lower edge of the lid free of obstructions, whereby the sponge-box may be more readily slipped onto the flange, the flat un- 65 obstructed lower edge of the wall serving to assist in guiding the box when it is slipped onto the flange.

The nature and scope of the invention having been thus indicated and its preferred embodiment having been specifically described, 70 what is claimed as new is:

In combination with a receptacle of the class set forth having a hinged top having a vertical dove-tail rib on its back wall, said 75 rib terminating short of the lower edge of said back wall, an absorbent-holder consisting of a box having an open top and one or more foraminous walls and one or more solid walls, one of the solid walls being provided 80 with an open-ended dove-tail groove adapted to frictionally fit the dove-tail flange on the cover.

In testimony whereof I hereunto affix my signature.

JESSE FRANKLIN PRATHER.
